UNITED STATES PATENT OFFICE.

ROBERT E. EWING, OF GLOUCESTER CITY, NEW JERSEY, ASSIGNOR TO WELSBACH
LIGHT COMPANY, OF GLOUCESTER CITY, NEW JERSEY, A CORPORATION OF NEW
JERSEY.

INCANDESCENT GAS-LAMP.

1,201,029.

Specification of Letters Patent.

Patented Oct. 10, 1916.

Application filed January 6, 1916. Serial No. 70,581.

To all whom it may concern:

Be it known that I, ROBERT E. EWING, a citizen of the United States, residing at Gloucester City, in the county of Camden 5 and State of New Jersey, have invented a new and useful Improvement in Incandescent Gas-Lamps, of which the following is a full, clear, and exact description, reference being had to the accompanying drawings, 10 forming part of this specification, in which—

Figure 1 is a view partly in side elevation, and partly in section, of the lamp, and Fig. 2 is a partial section taken at right angles to 15 Fig. 1, showing the indicator or arrow connection.

My invention relates to inverted incandescent gas lamps, and is designed to provide an improved lamp of this character in 20 which a substantially closed shell of general inverted conical form serves to inclose and conceal the valve operating mechanism, and at the same time to protect the same from heat.

25 In the drawings, in which I show my invention as applied to a semi-indirect cluster inverted lamp, 2 represents the gas supply pipe leading into the valve casing 3, having an ordinary type of ratchet valve 4, with the 30 valve lever 5 shown as projecting downwardly and operated by flexible connections 6 extending over a pulley 7 mounted on the inverted cone 8. In the form shown, 9 is the air shutter, 10 the mixer tube, 11 the manifold and 12 the burner tips for the inverted incandescent lamps. Above the manifold, if a multiple burner is used, I secure a circular or annular deflector 13, (which is preferably of greater diameter than the burner 35 cluster) of less diameter than the largest diameter of the conical shell 8. This lower deflector 13 serves to start the products outwardly in an annular stream. Above this deflector 13 and surrounding the Bunsen 40 tube, air shutter and valve, I provide an inverted conical shell 8 which is preferably of metal and enameled on its outer surface, although it may be made of other material. This inverted cone may, of course, have its 45 outer surface curved or straight, but is preferably substantially closed to the entrance of products of combustion. It preferably has a lower hole 14 through which the pilot tube 15 extends, this tube practically filling the hole, and it may have an upper hole or

holes 16 to receive hook screws 17 and to receive chains 18 for supporting the glassware. These hook screws, if used, preferably screw into spider-arms 19 projecting from a collar 20 secured to the mixture tube 60 inside the inverted cone. The chains may support an annular globe holder 21, as shown in Fig. 1, or may extend through piercings in the glassware itself. In the form shown, I have illustrated a semi-indirect globe 22 concealing the mantles and burners. 65

The inverted cone may terminate in an ornamental upper collar portion 23 which may be pierced ornamenteally and provided with 70 an inner ring 24 of different color, or it may be provided with an external ornamental ring 25 secured thereto. This upper part may be pierced for a shaft 26 secured to the valve plug and having at its outer end an arrow 27 to indicate whether the gas is turned on or off. 75

The invention is applicable to any inverted lamp, whether single or multiple, and many variations may be made in the structure of the lamp without departing from my invention. 80

The advantages of my invention result from the use of the inverted cone which is substantially closed to the products of combustion and serves the two functions of concealing the valve mechanism, etc. and of keeping down the temperature of these parts. The added deflector at the bottom of the cone is of considerable advantage in 85 starting the outward curved path of the products of combustion which thus do not strike the cone until they reach its intermediate portion. In actual practice it is found that this construction keeps the valve 90 casing and allied parts quite cool and effectively prevents the products of combustion from reaching the inlet, while concealing the parts. 95

I claim:—

1. In an inverted incandescent gas lamp, a mixture tube, an inverted cone surrounding the depending mixture tube and substantially closed to the products of combustion and globe holding devices connected to 105 said tube within the cone; substantially as described.
2. In an inverted incandescent gas lamp, a mixture tube, an inverted cone surrounding the depending mixture tube and sub- 110

stantially closed to the products of combustion, said cone serving to conceal the valve casing and allied parts, a globe holding ring, and suspending devices for the globe holding ring connected to the mixture tube within the cone; substantially as described.

3. An inverted incandescent gas lamp having a mixture tube, a gas valve connected to the mixture tube, an inverted cone surrounding the mixture tube and gas valve, said cone serving to conceal the valve and the lower portion of the mixture tube, an annular deflector below the inverted cone, there being an opening through the lower portion of the inverted cone and through the deflector, a pilot tube within the inverted cone extending through said openings to a point adjacent to the burner of the lamp, and globe supporting devices within the cone having members extending through the walls thereof for supporting the globe; substantially as described.

4. An inverted incandescent gas lamp having a mixture tube, a gas valve connected to the mixture tube, an inverted cone surrounding the mixture tube and gas valve, said cone serving to conceal the valve and the lower portion of the mixture tube, an

annular deflector below the inverted cone, there being an opening through the lower portion of the inverted cone and through the deflector, a pilot tube within the inverted cone extending through said openings to a point adjacent to the burner of the lamp, globe supporting devices within the cone having members extending through the walls thereof, a globe supporting ring, and chains connected to said ring and to the members extending through the cone; substantially as described.

5. In an inverted incandescent gas lamp, a mixture tube, an inverted cone surrounding the depending mixture tube and substantially closed to the products of combustion, globe holding devices connected to said tube within the cone, and an annular deflector below the inverted cone, said annular deflector being of smaller diameter than the largest diameter of the cone; substantially as described.

In testimony whereof, I have hereunto set my hand.

ROBERT E. EWING.
